UNITED STATES PATENT OFFICE.

ELDOR H. MOE, OF SALT LAKE CITY, UTAH.

ORE-CONCENTRATOR.

972,463.

Specification of Letters Patent. Patented Oct. 11, 1910.

Application filed November 26, 1909. Serial No. 529,984.

To all whom it may concern:

Be it known that I, ELDOR H. MOE, citizen of Norway, residing at Salt Lake City, in the county of Salt Lake and State of Utah, have invented certain new and useful Improvements in Ore-Concentrators, of which the following is a specification.

This invention relates to ore concentrators and has for its object the provision of a strong, durable and thoroughly efficient machine of this character, in which the separation of the material is effected by centrifugal force.

A further object to provide a concentrator including a revolving drum having a circumferential series of longitudinal separating tubes or chambers secured thereto and through which the ore is fed to receiving troughs.

20 A further object is to provide means connected with the separating tubes or chambers for positively directing the middlings, concentrate and residue into their respective receiving troughs.

25 A further object is to provide means for changing the angle or inclination of the drum with respect to the supporting frame thus to accelerate or retard the flow of material through the separating tubes.

30 A still further object of the invention is generally to improve this class of devices so as to increase their utility, durability and efficiency.

35 Further objects and advantages will appear in the following description, it being understood that various changes in form, proportions and minor details of construction may be resorted to within the scope of the appended claims.

40 For a full understanding of the invention and the merits thereof and also to acquire a knowledge of the details of construction and the means for effecting the result, reference is to be had to the following description and 45 accompanying drawings, in which:

Figure 1 is a longitudinal sectional view of an ore concentrator constructed in accordance with my invention; Fig. 2 is a front elevation of the same; Fig. 3 is a transverse 50 sectional view taken on the line 3—3 of Fig. 1; Fig. 4 is a transverse sectional view taken on the line 4—4 of Fig. 1.

Corresponding and like parts are referred to in the following description and indicated

in all the views of the drawings by the same 55 reference characters.

The machine comprises a supporting frame including spaced longitudinally disposed sills 5 connected by transverse bars 6 and 7, to one of which are connected in any 60 suitable manner converging side bars 8, there being spaced uprights 9 secured to the other transverse bar and connected through the medium of rearwardly and upwardly inclined bars 10, the latter being bolted or 65 otherwise secured to the converging ends of the side bars 8, as shown.

Disposed within the lines of the uprights 9 are arcuate bars 11 having their opposite ends recessed at 12 for engagement with the 70 rear transverse bar 7 and a similar transverse bar 13 connecting the upper portions of the uprights 9.

The lower longitudinal edges of the arcuate bars 11 are formed with teeth 15, while 75 the upper longitudinal edges thereof are provided with laterally extending flanges 16, which form a guide for a slide or carriage 17. The carriage 17 comprises a plate 18 which extends across the upper longitudinal edges of the arcuate bars 11 and is provided with oppositely disposed overhanging flanges 19 which embrace the flanges 16 of said arcuate bars, there being a recess 20 formed in the plate 18 and a corresponding recess formed in an auxiliary 80 detachable plate 21 and registering with the recess 20 to form a bearing for the lower end of a main operating shaft, indicated at 22.

Pivots mounted between the upper ends of the converging side bars 8, is a supporting member or bracket 23 having spaced vertically disposed lugs 24 provided with transversely aligned perforations to permit 95 the passage of pivot pins or bolts 25, the latter being extended through the adjacent ends of the converging side bars 8 so as to permit free oscillation of the bracket between the side bars.

The bracket 23 forms a bearing for the upper end of the operating shaft 22, there being registering recesses formed in the bracket and a plate 26 secured to the bracket to accommodate the shaft 22, as shown.

Keyed or otherwise rigidly secured to the operating shaft 22, is a conical shaped drum 27, the lower end of which is disposed con-

100

105

centric with the shaft 22 and provided with a transverse strengthening plate 22', while the upper end thereof supports a hopper 28, the ore and water being delivered to the 5 hopper through the medium of a flexible tube or conductor 29. Surrounding the conical shaped drum 27 and secured thereto in any suitable manner, are a circumferential series of longitudinally disposed inclined 10 separating tubes 30 through which the material is fed to the receiving troughs. The opposite side walls of the tubes 30 are preferably disposed parallel with each other, while the outer walls thereof are curved or 15 rounded, as indicated at 31 in Fig. 3 of the drawings.

Surrounding the lower end 32 of the drum, is a receptacle 33 having a plurality of upright partitions 34 defining independent 20 receiving troughs 35, 36 and 37, the metal forming the inner end of the trough 37 being extended upwardly to form a central tubular portion 38 having a depending flange 37' disposed within and spaced from 25 the cylindrical portion 32 of the drum, as shown.

The receptacle 33 is rigidly secured to the slide or carriage 17 by one or more inclined braces 39, preferably disposed at the cylindrical portion 38.

As a means for positively directing the different grades of material into their respective troughs, there are provided a plurality of sets of funnel shaped plates 40 spaced apart to form an intermediate passage for the material, the passage between each set of plates communicating at its upper end with the several tubes or chambers and at its lower end with the adjacent receiving trough.

The outer walls of the receptacle 33 and the partitions 34 are each preferably formed with laterally extending flanges 41 to assist in preventing the material in one receiving 45 trough from entering an adjacent receiving trough, there being a spout 42 depending from each receiving trough to permit the discharge of the material. The upper end of the shaft 22 is extended longitudinally 50 beyond the bracket 23 to permit the attachment of a pulley 43, the latter being connected through the medium of a belt 44 with an engine or other suitable source of power for rotating the drum 27.

55 As a means for raising and lowering the lower end of the drum 27 thus to accelerate or retard the flow of material through the separating chambers or tubes, there is provided a transverse shaft 45 having its opposite ends journaled in perforated lugs 46 depending from the flanges 19 of the carriage.

Spaced pinions are secured to the shaft 45 for engagement with the teeth on the rack 60 15, there being a hand-wheel 47 secured to

one end of the transverse shaft 45 so that by rotating the hand wheel, the lower end of the drum may be adjusted in the arc of a circle on the arcuate bars 14, for the purpose before mentioned.

73 Thus it will be seen that ore and water fed into the hopper 28 through the conductor 29 will enter the separating compartments or tubes 30 and will be thrown outwardly by centrifugal force, the finer 75 particles or concentrate adhering to the curved walls of the separating tubes, the middlings assuming a central position within the tubes and the residue collecting around the inner edges of the tubes and 80 against the outer face of the drum 27, as best illustrated in Fig. 3 of the drawings.

As the drum 27 revolves, the concentrate will be delivered through the passage formed between the outer set of plates 40 into the 85 receiving trough 35 for delivery through the spout 42 to the launder and the middlings will pass through the passage between the intermediate set of plates into the chamber 36 and thence be fed through the spout 90 42 into a receptacle for future delivery to the hopper 28, while the residue will pass through the passage between the inner set of plates into the trough 37 and thence off to the tailing dump.

95 In order to change the angle or inclination of the drum and its associated parts with respect to the supporting frame, it is merely necessary to rotate the hand wheel 47 until the desired adjustment is effected 100 and subsequently rotate the clamping screws 43, which latter engage the flanges 16 and serve to lock the drum in adjusted position.

Attention is here called to the fact that the strands of the belt 44 are disposed on opposite sides of the pivot bolts or pins 25 so that the belt 14 constantly maintains the proper tension regardless of the angle or inclination assumed by the hopper.

Having thus described the invention, what 110 is claimed as new is:

1. An ore concentrator including a supporting frame, a bracket pivotally mounted on the frame, spaced arcuate rack bars secured to the frame, a carriage slidably mounted between the rack bars, an operating shaft journaled in the bracket and carriage respectively, a drum mounted for rotation with the shaft and provided with a plurality of circumferential separating compartments, 115 a series of receiving troughs, means for positively directing the different grades of material into their respective receiving troughs, and pinions carried by the carriage and adapted to engage the teeth on the racks for moving the drum to different positions of angular adjustment with respect to the supporting frame.

120 2. An ore concentrator including a supporting frame, a bracket pivotally mounted 125

on the supporting frame, spaced arcuate 5
rack bars secured to the frame, a carriage
slidably mounted between the rack bars, an
operating shaft journaled in the bracket and
carriage respectively and having one end
thereof projected longitudinally beyond the
bracket and provided with a pulley, a drum
10 mounted for rotation with the shaft, a plu-
rality of open-ended separating tubes car-
ried by the drum, a hopper communicating
with the tubes at the upper ends thereof, a
plurality of receiving troughs, means for
positively directing the different grades of
material into the adjacent troughs, pinions
15 carried by the carriage and adapted to en-
gage the teeth on the racks for adjusting the
drum with respect to the frame, and a belt
engaging the pulley and having its opposite
legs disposed on opposite sides of the pivotal
20 axis of the bracket.

3. An ore concentrator including a sup-
porting frame, a bracket pivotally mounted
on the frame and provided with a bearing,
spaced arcuate rack bars secured to the
25 frame and provided with laterally extending
flanges, a carriage having a bearing and

provided with overhanging flanges engaging
the flanges on the rack bar, an operating
shaft journaled in the bearings of the
bracket and carriage respectively, a conical 30
shaped drum carried by the shaft and pro-
vided with a plurality of spaced radiating
separating compartments, a receptacle se-
cured to the carriage partitions disposed
within the receptacle and defining independ- 35
ent receiving troughs, means for positively
directing the different grades of material
from the separating tubes into the adjacent
troughs, a stub shaft journaled on the car-
riage, pinions secured to the stub shaft and 40
engaging the teeth on the racks for chang-
ing the angle or inclination of the drum, and
clamping screws piercing the flanges of the
carriage and engaging the flanges on the
rack bars for securing the drum in adjusted 45
position.

In testimony whereof, I affix my signa-
ture in presence of two witnesses.
